UNITED STATES PATENT OFFICE.

JAMES N. WILSON, OF MINNEAPOLIS, MINNESOTA, ASSIGNOR TO THE PIONEER THRESHER COMPANY, OF SAME PLACE.

THRASHING-MACHINE.

SPECIFICATION forming part of Letters Patent No. 507,771, dated October 31, 1893.

Application filed April 27, 1893. Serial No. 472,006. (No model.)

To all whom it may concern:

Be it known that I, JAMES N. WILSON, a citizen of the United States, residing at Minneapolis, in the county of Hennepin and State 5 of Minnesota, have invented certain new and useful Improvements in Thrashing-Machines; and I do hereby declare the following to be a full, clear, and exact description of the invention, such as will enable others skilled in the 10 art to which it appertains to make and use the same.

My invention relates to thrashing machines. The invention was especially designed for use on thrashing machines equipped 15 with automatic band cutting and feeding mechanism; but certain parts of the invention are also applicable or capable of use on hand fed machines.

The principal features of invention are directed to the control or regulation of the supply of the stock to the thrashing mechanism, by positive controlling or regulating devices, located in advance of and operated by the 20 thrashing mechanism itself.

In order to secure rapid and efficient work, it is necessary that the thrashing mechanism should never become clogged or choked down. To meet the demands of the business, the same machine must be capable of thrashing 25 many kinds of grain, seeds, and other stock; and each kind of stock will differ widely at different times and places, in condition, both as to the presence or absence of foreign materials, the presence or absence of moisture, 30 relative dryness, toughness, &c. At the same time, the machine must have large capacity, to receive consideration in the great wheat fields of the Northwest. To provide a machine which will meet all the above noted requirements, has been found a difficult task.

The problem has been solved in part, by the interposition of a governor, through which the feed mechanism is driven from the thrashing mechanism; by which arrangement the feed 40 mechanism will be stopped, whenever the thrashing mechanism slows down to a certain point, and will be started into action again, whenever the thrashing mechanism regains its full working speed. This plan has proven 45 in practice to be only a partial solution, for the reason that the stoppage of the feed

cannot, thereby, be made sufficiently quick. The margin of storage in such a governor, must be sufficient to drive the feed mechanism; hence, the thrashing cylinder, or other 55 form of thrashing mechanism, must slow down to a corresponding extent before the governor will let go of the feed mechanism. This margin of continued movement to the thrashing mechanism, will permit enough more stock to 60 be drawn in, oftentimes, to completely choke down the machine. To overcome this difficulty and complete the solution, by providing a positive cut-off, located in advance of and operated by the thrashing mechanism itself, 65 which becomes instantly effective, to intercept the stock, whenever the thrashing mechanism loses its proper working speed; and my device is preferably constructed in the form of a pair of combs, one overhanging and 70 the other underlying the path of the stock and movable across the same and out of the same, under either the direct or indirect control of the thrashing mechanism.

As another feature of invention, I drive the 75 feed mechanism by a belt, which is subject to the action of a belt controller operated either directly or indirectly by the thrashing mechanism, to render the said belt operative or inoperative on the feed mechanism, accord- 80 ing to whether the thrashing mechanism has or has not the proper working velocity.

From the foregoing, it will be seen that both the cut off device and the belt controller are operated directly or indirectly from the 85 thrashing mechanism itself. In my preferred arrangement, I operate the said parts indirectly through a governor, which is driven directly from the thrashing mechanism.

Other details of invention will appear from 90 the following description, and will be defined in the claims.

A machine embodying my invention is illustrated in the accompanying drawings, like letters referring to like parts throughout the 95 several views.

Figure 1 is a right side elevation of the front part of the thrashing machine. Fig. 2 is a vertical central longitudinal section through the same. Fig. 3 is a vertical cross 100 section on the line X X' of Fig. 1, looking toward the rear; and Fig. 4 is a vertical central

longitudinal section through the thrashing mechanism, illustrating a modified construction, for controlling the cut off device from the thrashing mechanism. Fig. 5 is a longitudinal vertical section illustrating my preferred form of feeding mechanism.

a is the main frame of the thrashing machine, and a' is a band cutter and feeder frame, extended forward from the mouth of the thrashing machine and supported by the braces a² and the main frame a.

b b' represent the thrashing mechanism proper, which may be either of the cylinder and concave type, as shown, or of any other suitable kind, so far as the application of my invention, in a broad point of view, may be concerned.

c represents a separating carrier, in diagram, to the rear of the thrashing mechanism, and c' the grain belt or apron, all of the well-known standard construction.

b² is the cylinder cap or deck, and c² the main or separator deck.

d is a rotary band cutter journaled in the frame a', of any suitable kind, preferably with feathering shafts d', for carrying the knives d². The means for feathering the same may be of any suitable kind.

d³ represents a feed cylinder located to the rear of the band-cutter d, and shown as provided with teeth d⁴.

d⁵ is a deck over the band cutting and feeding mechanism, and provided with a rearward extension d⁶, for covering certain parts which will later appear.

d⁷ d⁸ is a divided head-board, from the deck d⁵ to the hood b², the upper section d⁷ of which, is held normally against a stop d⁹ by a spring d¹⁰. This construction permits the spring held upper section d⁷ to yield, if necessary.

f is a feed-board pivoted to the concave b' and upheld by a button f', and may be dropped at will, to give access to the cylinder and concave.

f² is an angular deck, arranged vertex upward between the side-boards of the feeder-frame a', with its inner or delivery end, directly over the feed-board f, and its outer or receiving end a short distance back of the end of the frame a'.

f³ is an endless feed carrier, of the chain and toothed slat variety, which traverses the deck f², and is driven by sprocket wheel shafts f⁴ and f⁵, located at its inner and outer ends respectively. It is also guided by a similar sprocket-wheel shaft f⁶, located at the angle of the deck f², and is subject to the action of a yielding tightening device f⁷, shown as in the form of a sprocket wheel shaft, the wheels of which are of the cup variety, for engaging with the slats of the under fold of the carrier. The tightener f⁷ is journaled in sliding boxes f⁸, seated in the side-boards of the frame a', and upheld by springs f⁹.

f⁵ The outer carrier shaft f⁵ has a gear f¹⁰, on its right end, as shown, engaging through an intermediate gear f¹¹, with a gear h, on the

upper end carrier-shaft h', of a bundle carrier h², shown as of the slat and belt variety, traversing the lower or outer end carrier shaft h³ and a deck h⁴, of a divided or sectional carrier frame h⁵ h⁶, which parts taken together constitute the bundle-table. The outer section h⁶ is hinged, as shown at h⁷ to the inner section h⁵, and is normally upheld at its outer end by pivoted legs h⁸. The sections h⁵ and h⁶ are rendered rigid with each other, at the hinge point h⁷, by a snap hook h⁹ carried by the section h⁶, engaging a lock-bar h¹⁰, on the section h⁵. The section h⁶ is adapted to fold inward over the top of the section h⁵, and be held by a snap-hook h¹¹, on the section h⁵, engaging with a projection h¹² on the section h⁶. The upper section h⁵ is pivoted to the band-cutter and feeder frame a', at a point forward of its delivery end, as shown at h¹³, and is adapted to fold under the band-cutter and feeder frame into the dotted line position, as shown in Fig. 1, where it will be held by a snap-hook h¹⁴, engaging a suitable lug h¹⁵. Under the pivotal movement of the section h⁵, the upper and carrier-shaft gear h, will be thrown into or out of engagement, with the intermediate gear f¹¹ and the gear f¹⁰ of the outer end feed-carrier shaft f⁶.

The above described feed mechanism has certain points of advantage, which will be noted when stating the general operation of the machine.

Turning now to the more important features of the invention and referring to Figs. 1, 2 and 3, especially, k k' are the pair of co-operating parts, preferably of comb-like form, as shown, constituting together my automatic cut-off or feed throat opening and closing device. Of the said parts, the upper member k is loosely seated for vertical movement in guides k², formed in the sides of the main frame a; and the lower part k' is pivoted in the side-boards of the main frame a, and normally underlies the path of the stock at the junction of the feed-board f with the concave b'. This comb k' may be constructed in any suitable way, but is preferably made up of a series of fingers separated by collars and all mounted on a rectangular shaft, the ends of which project through the frame, and are provided with crank-arms k³ connected by rods or links k⁴ to the upper member or comb k, by means of projecting brackets k⁵, the projecting portions of which extend outward through slots k⁶, in the side-boards of the main frame a. The upper member k is carried on the forward end of a pivoted lever k⁷, having a slot and pin engagement, as shown at k⁸, with a bracket k⁹, rising from the center of the comb k. The lever k⁷ is pivoted intermediate its extremities to a fixed bracket k¹⁰, forming a part of the governor-support k¹¹, and is connected at its inner end by a slot and pin connection g, with the governor stem g' of an ordinary ball governor G. The governor G is driven from the thrashing cylinder b by a belt g², passing over a pulley b³, on

the left end of the cylinder shaft, and over the governor pulley g^3 .

The bracket k^{10} and the pivoted lever k^7 , are provided with a series of holes k^{12} , for the 5 pivot pin k^{13} , in order to afford a variable fulcrum to said lever, for giving to the co-operating cut off combs $k\ k'$ any desired quickness or speed of action.

One of the projecting brackets k^5 has pivotally attached thereto one end of an outside lever n , pivoted to the right side board of the main frame a , as shown at n' , and having its rear end connected by a link n^2 with the rear end of a belt controlling lever n^3 , pivoted to 15 the main frame, a , below the cylinder, and carrying on its front end a roller n^4 , applicable to the feed carrier driving belt n^5 . This belt n^5 passes over a pulley b^4 , on the right end of the cylinder shaft, and a pulley n^6 on 20 a cross shaft n^7 , and provided on its inner hub with a pinion n^8 , engaging a gear n^9 on the right end of the inner feed carrier shaft f^4 . The feed driving belt n^5 is also subject to the action of an adjustable belt tightener n^{10} . 25 This tightener n^{10} serves to set the belt n^5 with the proper amount of slack, for permitting the belt controller n^3 to have its proper action as operated by the governor, for rendering the belt n^5 operative or inoperative, according to whether the thrashing cylinder b has 30 or has not the proper working velocity.

The different parts have now been specified, and the operation of the same may be briefly described as follows:—The stock will 35 be supplied by the bundle carrier h^2 and delivered to the band-cutter d , and the feed carrier f^3 , under the co-operation of which parts, the bands will be cut, if the stock is in the bundle form, and be carried forward and 40 in co-operation with the feed cylinder d^2 , will be delivered to the thrashing mechanism with a free sliding feed. In respect to the action of the feeding mechanism, it is only necessary to note that the angular form of the deck 45 f^2 and the co-operating feed carrier f^3 , will give to the stock the proper elevation, for delivering the same to the feed cylinder, at a point high up on its receiving side, and as near as practicable on a tangent thereto. As 50 is well known, this is the most desirable delivery to the feed cylinder; and the angular deck f^2 may be extended upward even higher, than shown in the drawings, for still bettering the action in this respect. Both the bundle 55 carrier deck h^4 and the feed carrier deck f^2 are continuous or solid, and the chains of the feed-carrier f^3 work in longitudinal slots, (not shown) on the face of the deck f^2 , so as to bring the slats of the carrier flush with the 60 face of the deck and insure the carrying forward thereby of all the shattered grain. In case a big bunch of stock should check the motion of the feed-carrier f^3 , the tightener f^7 will yield and thereby prevent any breakage. 65 As long as the thrashing cylinder b is running up to its full working velocity, or beyond the same, the upper comb k , will be held by the

governor in its raised position, and the lower comb k' in its lowest position, so that the feed throat to the cylinder will be wide open. If, 70 by the entrance of a matted or tough bunch of stock, the cylinder b should slow down below the proper working velocity, the governor will immediately throw down the upper comb k and throw up the lower comb k' across the 75 path of the stock, thereby intercepting the stock and closing the feed throat, with a practically instantaneous action. It will not be possible, therefore, for the cylinder to pull in any additional stock, even if there were a 80 considerable quantity on the delivery section of the feed carrier f^3 . The cylinder will therefore quickly recover working velocity, at which time the governor will again throw the combs $k\ k'$ into their normal or throat opening 85 position. It will be noted that the fulcrum k^{13} , for the lever k^7 , which communicates the motion from the governor stem g' to the combs $k\ k'$, is so located as to give to the combs a relatively large movement for any given 90 movement of the governor stem. This leverage may be made such, and the governor may be run at such a speed, with reference to the speed of the cylinder b , as to make the cut-off extremely sensitive, or as sensitive as necessary for the work in hand. The movement of the upper comb k , to effect the cut-off, under the control of the governor, will also operate the lever n and the belt controller $n^3\ n^4$, so as to release or loosen up the belt n^5 and 100 render the same inoperative on the feed carrier. This release of the feed driving belt n^5 will be practically simultaneous with the cutting off action of the combs k and k' . The feed carriers and their connections will, 105 under the action of the momentum of their parts be given a slight continued feeding movement. As is obvious, however, the feed of the stock to the thrashing cylinder was positively intercepted by the closing of the throat 110 opening and closing device. When the governor again throws the combs into their open position, which will occur as soon as the cylinder regains its proper working velocity, as before stated, the belt tightener n^8 will be 115 thrown into its tightening position, so as to again render the feed driving belt n^5 operative on the feed-carrier f^3 . Upon the thrashing cylinder again acquiring its proper working velocity, the throat opening and closing devices will open, in advance of the starting of the feed-carrier f^3 , in consequence of the inertia of said feed-carrier f^2 , and its connected parts, which must of course, be overcome in 120 starting the same. 125

From the foregoing it is obvious, that the thrashing mechanism proper can never choke down. The thrashing machine proper may, therefore, be kept in continuous action, greatly increasing its capacity and effecting 130 a large economy, both in the gain in the quantity of the work done and in the prevention of breakage; and also in the prevention of waste by the passing of unthrashed stock,

which necessarily occurs when the cylinder becomes choked down or slugged.

If, at any time, there should be an undue accumulation of stock between the delivery end 5 of the feed-carrier f^3 and the head-board d^7 and d^8 , the same will be thrown back out toward the front of the machine by the feed cylinder d^8 and the band-cutter d . Likewise, if there should be an undue accumulation 10 between the band cutting cylinder d and the feed-cylinder d^3 , the excess will be carried over the band cutting cylinder and be thrown forward onto the bundle carrier h^2 .

Referring now to the modification shown 15 in Fig. 4, I dispense with a governor and rely on a part of the thrashing mechanism itself, to directly control the cut-off and the feed driving belt controller. The combs p and p' are identical with the forms shown in the main 20 views; but instead of being connected to a governor together, the upper comb p is connected by a bell-crank lever p^2 to the rear end of a spring-held sliding concave hanger p^3 , and the lower comb p' has its crank arm p^4 connected by a link p^5 , directly to the front end of the said sliding concave p^3 . The concave p^3 is guided at its rear end by a fixed cross rod p^6 , passing through a slot p^7 in the concave hanger. The concave hanger and 25 concave are normally held in their forward or working position, by strong springs p^8 , shown as encircling the guide-rods p^9 , carried by brackets p^{10} on the concave hanger, and working through a fixed stop-bar p^{11} . The tension of the springs p^8 may be adjusted by jam-nuts p^{12} . The concave hanger p^3 is supported 30 at its forward end by hanger links p^{13} , pivoted to the side boards of the main frame a . The concave hanger p^3 has rigidly secured to 35 its forward end a belt tightener p^{14} , which in the normal position of the concave hanger, bears against the feed driving belt n^5 , and renders the same operative. The action is as follows:—The tension from the springs p^8 40 is sufficient to hold the concave hanger in its forward or normal position, for the normal and proper working of the thrashing mechanism, or at all times, except when slugged or overloaded with stock. If a matted or tough 45 bunch of stock should gain entrance to the thrashing mechanism, of a character which would otherwise choke down or slug the machine, the concave hanger p^3 will yield against the springs p^8 sufficient to relieve the excessive strain on the parts and release the stock. 50 In this action, the front end of the concave hanger p^3 will move downward and backward, in the arc of any desired circle, depending upon the radius link p^{13} , in point of location 55 or length; while the rear end of the said concave hanger p^3 will be constrained by the rod p^6 and the slot p^7 to a straight line action, thereby preventing the concave from following up the cylinder, and giving an enlarged 60 and free delivery from the cylinder. At the same time that the concave hanger p^3 moves 65 backward, the combs p and p' will be thrown

into their closed position, by the bell-crank lever p^2 , the link p^5 and the crank-arm p^4 , thereby intercepting the stock and closing 70 the feed-throat. After the release has taken place, the spring p^8 will throw the concave hanger p^3 back, into its normal position, and, through the connections just described, will again open the feed-throat. The rearward 75 movement of the concave hanger, will also retract the belt-tightener p' from the feed driving belt n^5 , rendering the said belt inoperative and stopping the feed-carrier f^3 ; and on the return of the concave hanger, the said 80 belt-tightener p' will again render the said belt n^5 operative.

The driving connections for the band cutting cylinder d and the feed-cylinder d^3 , have not been shown and the said band-cutter and 85 feed-cylinder have only been indicated in diagram, as they may be of any suitable kind, and the driving connections be applied in any suitable way.

It should perhaps be noted, that the upper 90 section h^5 of the bundle table is limited in its outfolding position toward the working face of the feed-carrier f^3 , by stop-blocks h^{16} , on the band cutter and feeder frame a' . This is for the purpose of properly spacing the 95 gears, h, f^{11} and f^{10} , when the bundle-table is in its working position.

The feed-board f has on its face a flexible 100 guard f^{12} , for preventing the feed-carrier f^3 from drawing back the shattered grain or any 105 of the stock beyond the feed-board.

For the clearing action of the band cutting cylinder d , the feathering knives d^2 are shown as provided with rearward projections d^{24} , which serve as clearing teeth.

Referring to Fig. 5, wherein I show my preferred form of feed mechanism, I dispense with the rotary feed cylinder, shown in Figs. 1 and 2, and substitute an endless carrier r , of the chain and toothed slat variety, which 110 is mounted on sprocket wheel shafts $r' r^2$ journaled in a double deck carrier frame r^3 . The carrier frame and carrier, are free to swing on the upper shaft r^2 , as a pivot; and the journals of the lower shaft r' project 115 through slots r^4 in the feeder frame side-boards a' . This construction permits the said carrier and carrier frame $r r^3$, to float on the stock at its lower or inner end, with freedom for a limited rising and falling motion determined 120 by the length of the slots r^4 . Motion is imparted to the carrier r , to move the same in the direction shown by the arrows, at a slightly greater speed than the lower feed carrier f^3 . This motion is imparted in any suitable way, 125 as by a chain r^5 running over a sprocket r^6 on the shaft r^2 , and a sprocket r^7 on the cross shaft n^7 , these sprocket wheels and chain above referred to, being shown in dotted lines only.

With the construction shown in Fig. 5, a fixed head-board r^8 is employed. A shield or face-plate r^9 projects downward from the inner or lower end of this head-board r^8 , directly

in front of the upper member k of the cut-off combs.

It should be noted that the carrier r and its frame r^3 , extends upward beyond the angle of the lower deck f^2 and its carrier f^3 ; and that the band cutting cylinder d , overhangs the outer inclined face of the deck f^2 and the carrier f^3 . In virtue of this location of the parts, the band cutter works to an advantage on the bundles, and the forward ends of the cut bundles will be caught and whipped in by the upper carrier r , and be, thence, carried forward by the co-operating surfaces of the two carriers. As the upper carrier runs faster than the lower carrier f^3 , the stock will be fed from the top with a sliding feed. Any number of desired divisions of the cut bundles can be made, according to the relative speeds of the carriers r and f^3 .

Both sections of the double deck r^3 are continuous, and the chains of the carrier run in grooves (not shown) thereon, so that the slats run flush with the deck surfaces.

The band cutting cylinder d , in respect to its clearing action, on the stock, which may accumulate between the upper feed carrier and the said cylinder, will operate in substantially the same way, as when co-operating with the feed cylinder d^3 , the teeth $d^{2\frac{1}{2}}$ serving to throw forward onto the bundle carrier h^2 any excess of stock which may be carried in by the band cutting cylinder.

If, when the cut off to the thrashing cylinder occurs, or at any other time the stock should accumulate at the inner or lower ends of the feed carriers, the upper carrier r will carry the same back above the deck r^3 and deliver the same to the teeth $d^{2\frac{1}{2}}$ of the band cutting cylinder d , which will throw the same to the front onto the bundle carrier h^2 . This function is of considerable importance, in its relation to the cut-off mechanism hereinbefore shown and described, as used in this machine.

What I claim, and desire to secure by Letters Patent of the United States, is as follows:

1. The combination with the thrashing mechanism, of an automatic positive cut off device in advance of and controlled by the thrashing mechanism for positively intercepting the stock whenever the thrashing mechanism loses proper working speed, substantially as described.

2. The combination with the thrashing mechanism, of a feed throat opening and closing device in advance of and controlled by the thrashing mechanism, operating to positively open and close said feed throat according to whether the thrashing mechanism has or has not proper working velocity.

3. The combination with thrashing mechanism, comprising the cylinder and concave, of the feed throat opening and closing device, consisting of a pair of cooperating parts mounted for movement, one from above and the other from below, across the path of the stock, and intermediate connections to said

throat opening and closing device operated by said thrashing mechanism, whereby under an excessive feed of stock between said cylinder and concave, sufficient to reduce the speed of said cylinder below proper working velocity, said throat opening and closing device will close and positively intercept the stock and will be again opened, automatically when the working velocity of said cylinder has been restored, substantially as described.

4. The combination with thrashing mechanism, of a governor driven therefrom and a positive cut off device, in advance of the said thrashing mechanism, with intermediate connections from said governor, for positively intercepting the stock whenever the thrashing mechanism loses proper velocity, substantially as described.

5. The combination with thrashing mechanism, of a governor driven therefrom and a feed throat opening and closing device, in advance of said thrashing mechanism, having connections with said governor, for positively cutting off or permitting the supply of stock, according to whether the thrashing mechanism has or has not proper working velocity.

6. The combination with thrashing mechanism, of a governor driven therefrom and a feed throat opening and closing device consisting of a pair of co-operating parts mounted for movement, one from above and the other from below, across the path of the stock, in advance of the thrashing mechanism, and intermediate connections from said throat opening and closing device to said governor, substantially as, and for the purpose set forth.

7. The combination with thrashing mechanism, of a governor driven therefrom and a feed throat opening and closing device consisting of a pair of co-operating comb like parts mounted for movement, one from below and the other from above, across the path of the stock, in advance of the thrashing mechanism, and intermediate connections from said throat opening and closing device to said governor, substantially as, and for the purpose set forth.

8. The combination, with the thrashing cylinder and concave, of an automatic feed mechanism for the same, a governor driven from said cylinder and a pair of movable combs one overhanging and the other underlying the path of the stock in advance of said cylinder and operating under the control of said governor, to open and close the feed throat, according to whether said cylinder has or has not proper working velocity.

9. The combination with the thrashing mechanism proper of a belt driven feed mechanism for the same and a pair of belt tightening devices, one operated by said thrashing mechanism proper, for rendering said feed driven belt operative or inoperative according to whether the thrashing mechanism has or has not proper working velocity, and the other of which is operative to set the belt

with the proper slack, substantially as described.

10. The combination with thrashing mechanism, of a belt driven feed mechanism for the same, a governor driven from said thrashing mechanism, and a belt tightener operated by said governor and applied to said feed driving belt, for rendering the said belt operative or inoperative, substantially as and for the purpose set forth.

11. The combination with thrashing mechanism, of a belt driven feed mechanism, a governor driven from said thrashing mechanism, and a pair of belt tightening devices applicable to said belt one securable by hand to set the belt with proper slack and the other controlled by said governor, for rendering the belt operative or inoperative according to whether the thrashing mechanism has or has not proper working velocity, substantially as described.

12. The combination with thrashing mechanism, of automatic feed mechanism for the same, a positive cut off device, in advance of the thrashing mechanism, and a governor driven from said thrashing mechanism and controlling both the said cut off device and said feed mechanism, substantially as described.

13. The combination with thrashing mechanism, of a belt driven feed mechanism for the same, a positive cut off device in advance of the thrashing mechanism, a belt controller applicable to said feed driving belt and a governor driven from said thrashing mechanism and operating said cut off device and said belt controller, substantially as described.

14. The combination with the band cutter and feeder frame, extending forward of the thrashing machine feed throat, of a bundle table comprising a sectional folding carrier frame, the lower section of which folds over the upper section and the upper section of which is pivoted to said feeder frame forward of its delivery end and folds under said frame, substantially as and for the purpose set forth.

15. The combination with the cutter and feeder frame, of the bundle table comprising the sectional folding carrier frame pivoted forward of its delivery end, to said feeder frame, to fold under the same, and having an upper end carrier gear engageable and disengageable with a driving gear on said frame, by the pivotal movement of said carrier frame, substantially as described.

16. The combination with the cutter and feeder frame a' of the feed carrier f^3 , the feed-carrier shaft f^6 , having the gear f^{10} , the intermediate gear f^{11} , the bundle carrier frame $h^5 h^6$, pivoted to said feed frame at h^{13} , and the bundle carrier driving shaft h' , having the gear h engageable with the gear f^{11} , substantially as described.

17. The combination with thrashing mechanism, of a positive cut-off device in advance of the same, for positively intercepting the

stock, a governor driven from said thrashing mechanism and controlling said cut-off device, and an adjustable lever, for communicating the motion from said governor to said cut-off device, whereby the speed of the cut-off may be varied for any given motion of the governor, substantially as described.

18. The combination with the thrashing cylinder and concave, of the ball governor G , the overhanging vertically movable comb k , the underlying pivoted comb k' , the pivoted lever k^7 connected at one end to the governor stem and at the other to said comb k , the crank-arm k^8 on the lower comb k' and the links k^4 connecting said cranks k^8 with the upper comb k , substantially as described.

19. The combination with the thrashing cylinder and concave, of the governor driven therefrom, the cutting-off combs $k k'$, the central pivoted lever k^7 connecting the lever with the upper comb k , the outside lever n operated by the upper comb k , the link k^4 , connecting the upper comb with the crank-arms k^8 on the lower comb k' , the feeder driving belt n^5 , the belt tightener $n^3 n^4$ and the link n^2 connecting said tightener with the lever n , substantially as and for the purpose set forth.

20. The combination with a thrashing cylinder, of a yielding concave hanger under spring tension to resist the pressure for normal work, and yielding to relieve excessive pressure, said concave being mounted for yielding motion on a line tending toward the travel of the stock and receding from the cylinder, substantially as described.

21. The combination with a thrashing cylinder, of a sliding concave hanger under spring tension restrained to substantially straight line sliding movement at its rear end and to movement at its forward end, in the arc of a circle of larger radius than the curvature of the concave, substantially as described.

22. The combination with thrashing mechanism, of a pair of endless feed carriers running face to face, the upper member of which carrier terminates short of the cylinder hood at its lower end, and is supported with clearance above the same, for permitting the said upper carrier to throw back to the front any excess of stock which may accumulate in the feed throat, substantially as described.

23. The combination with thrashing mechanism, of a pair of endless feed carriers, running face to face, the upper member of which carrier terminates short of the cylinder hood, at its lower end, and is supported with clearance above the same, and a combined band cutting and clearing cylinder overhanging the lower feed carrier, forward of the upper carrier, in position to receive any stock which may be returned by said upper carrier and to continue the return movement of the stock, substantially as described.

24. The combination with a thrashing mechanism, of an automatic feed throat opening and closing device, directly in advance of and

controlled by said thrashing mechanism, and a pair of endless feed carriers running face to face, the upper member of which carriers terminates short of the cylinder hood at its lower end, for permitting the said upper carrier to throw back to the front any stock which would otherwise accumulate when the feed throat is closed, substantially as described.

25. The combination with a thrashing mechanism, of an automatic feed throat opening and closing device, directly in advance of and controlled by said thrashing mechanism, and a pair of endless feed carriers running face to face, the upper member of which carriers terminates short of the cylinder hood at its lower end, for permitting the said upper carrier to throw back to the front any stock which would otherwise accumulate when the feed throat was closed, and a combined band cutting and clearing cylinder overhanging

the lower carrier forward of the upper carrier, substantially as described.

26. The combination with the thrashing cylinder and concave, of the the feed throat opening and closing device, the angular continuous 25 deck f^2 traversed by the lower feed carrier f^3 , the double deck carrier frame r^8 , traversed by the upper feed carrier r , pivoted at its upper end and free for a limited rising and falling motion at its lower end, and the rotary 30 band cutting cylinder d with clearing teeth $d^{2\frac{1}{2}}$; the said parts operating substantially as described.

In testimony whereof I affix my signature in presence of two witnesses.

JAMES N. WILSON.
